UNITED STATES PATENT OFFICE.

EMIL LASER, OF PATERSON, NEW JERSEY.

CARPENTER'S WORK SUPPORT.

Application filed September 17, 1925. Serial No. 56,867.

To all whom it may concern:

Be it known that I, EMIL LASER, a citizen of the United States, residing at Paterson, in the county of Passaic and State of New

Jersey, have invented certain new and useful Improvements in Carpenters' Work Supports, of which the following is a specification.

This invention relates to devices for supporting a door, window sash or other similar work while resting on the floor in an upright position while an edge thereof is being planed, as in fitting the door etc. to its opening. The object of the invention 10 is to provide a simple and efficient support of this class which the carpenter can use with facility by simply setting the support in place in some convenient building opening, as the opening for which the door to be 15 planed is designed.

The invention consists in certain novel combinations of parts substantially as hereinafter shown and described and finally embodied in the appended claims.

25 In the drawing,

Fig. 1 shows a door opening, with the support in place holding a door to be planed, which appears in section;

Fig. 2 is a front elevation and Fig. 3 a 30 plan of the support;

Fig. 4 is a vertical sectional view taken at one side of one of the clamping devices;

Fig. 5 is a front elevation, showing how the support may also be used for other purposes;

Fig. 6 is a vertical section on line 6—6 of Fig. 5; and

Fig. 7 shows a detail of Figs. 5 and 6.

1 in Fig. 1 represents a door opening, the 40 inner sides or opposing vertical faces of which are indicated at 2. The improved support is adapted to be fitted to the door opening, spanning the same and being held in position by bearing against the inner sides 45 2 thereof. For this purpose the support is constructed as follows:

3 3 designates two members in the form 50 of flat strips arranged face to face and parallel with each other, each preferably having an outer enlarged end 3^a which is shod with a cushion of rubber 3^b or other material which when the support is arranged as shown in Fig. 1 will obtain a good frictional grip on the side 2 of the door opening.

55 The members are slidable on each other longitudinally and to confine them to such

movement each has on its relatively inner end portion, and preferably pinned thereto, as at 4^a, a clip 4 which embraces the other member. These confining means are preferable because they afford a certain added 60 rigidity to the support when introducing it into and also when in operative position in the door opening.

Each member 3 has a longitudinal slot 5, 65 such slots being in registry with each other.

Clamping devices are provided which both clamp the two members 3 in the position to which they are adjusted and also afford cheek portions between which the 70 door is adapted to be received and held upright while being planed. The cheek portion of each device is indicated at 6; these portions are both arranged at the same side 75 of the support, or so as to bear against one of the members. Each has a threaded shank 7 which penetrates both slots of the members and protrudes therefrom. On the protruding threaded end of each shank is a washer 8 and a nut 9. 80

In using the device to support a door while planing the latter the carpenter forces the members apart so that their over-all length is a trifle greater than the width of the door opening and then clamps them in their thus-adjusted position by means of one of the clamping devices. He then sets the other clamping device the proper distance from the first so that the door may be received fairly snugly between the cheek portions 6, 90 whereupon he establishes this clamping device in clamping relation to the members. He then places the device in the door opening so as to span the same and then while holding one end in fixed position, abutting the side of jamb of the opening, he slides the other end over the surface of the opposite side of the door opening until the support is horizontal. Thereby the device will be firmly fixed in position and will afford 100 a rigid support for the door while being planed. Thus a firm support for the door, which is held by the support as shown in Fig. 1 while being planed, is afforded.

The support may also be used for other 105 purposes, as in Figs. 4 to 6 where a clamp of well-known type is shown adapted to hold a saw while being filed and which it is necessary to describe only by stating that a' is an elongated frame to rest on some 110 horizontal support (and carrying the saw-clamp a²), and a³ a bent arm depending

therefrom and having tapped into it a thumb-screw α^4 to coact with the frame, clamp-fashion, to grip the support. When this saw-clamp is to be fitted to my support I 5 preferably provide an adapter 10 in the form of a block having three arms which receive the members 3-3 in the manner shown best in Fig. 6. Against the top and bottom surfaces of this adapter bear the frame α' and 10 thumb-screw α^4 when the latter is screwed up to obtain clamping action, while the saw-clamp as a whole is kept from skewing around a vertical axis (through the thumb-screw) by contact of the cheek portions 15 with a vertical face of the saw-clamp.

One underlying novel feature of my device is that the two clamping devices for the members 3-3 of the support also afford means to receive the work. Another underlying novel feature consists in the employment, with the members 3-3 slideable on each other rectilinearly to an infinite number of 20 positions, of a plurality of clamping devices for said members spaced from each 25 other lengthwise of their path of sliding movement, whereby the device may be adjusted first to a little greater length than the width of the door opening and then forced as described from an initially inclined to 30 a substantially horizontal or jammed relation to the sides of the door, thus distinguishing from known supports of this class in which the members are pivoted together and are forced into operative relation to the door 35 opening by a toggle action.

Having thus fully described my invention what I claim and desire to secure by Letters Patent is:

1. In a support for the purpose described, 40 the combination of a pair of members each adjustable slidably and substantially rectilinearly on the other and respectively adapted to bear against the inner sides of a building

opening and be thereby supported, and a pair of devices for clamping said members 45 in the position to which they are adjusted having co-acting work-holding cheek portions projecting from said support, one of said devices being adjustable toward and from the other substantially parallel with 50 the path of adjustment of said members with respect to each other.

2. In a support for the purpose described, the combination of a pair of members having registering slots and each adjustable slidably on the other substantially lengthwise of 55 said slots and respectively adapted to bear against the inner sides of a building opening and be thereby supported, and a pair of devices for clamping said members in the 60 position to which they are adjusted having co-acting work-holding cheek portions projecting from said support, one of said devices penetrating the slots and being adjustable lengthwise thereof toward and from the 65 other.

3. In a support for the purpose described, the combination of a pair of elongated members each adjustable slidably on the other lengthwise thereof and respectively adapted 70 to bear against the inner sides of a building opening and be thereby supported, means on the relatively inner end portion of each member to confine the other member during adjustment to substantially longitudinal 75 movement, and devices arranged on the support and having co-acting work-holding cheek portions projecting therefrom, one of said devices being a clamp to clamp said members in the position to which they are 80 adjusted and one of said devices being adjustable on the support substantially parallel with the path of adjustment of said members on each other.

In testimony whereof I affix my signature.
EMIL LASER.
